COIN, BILL, AND CARD CASE

Nat W. Umansky, Brooklyn, N. Y.

Application October 29, 1935, Serial No. 47,231

6 Claims. (Cl. 150—35)

The present invention relates to coin, bill and card cases and more particularly to the type including a pocket mirror, the covering of which is provided with compartments.

5 The principal object of this invention is to provide an article of the character described wherein the mirror is covered with sheet components in novel combination to form various pockets and compartments of improved construction 10 specially adapted to receive calling cards, coins and paper money.

Another object is to provide an article of the class mentioned wherein the mirror is covered by sheet components in novel combination whereby 15 a pocket is formed, in which construction, continued use of the pocket by insertion of articles therein and their extraction therefrom, will not cause said components to be loosened or become disengaged from one another or from the frame 20 member of the unitary structure.

A further object of this invention is to provide an improved means for holding bills, of a design and construction which is novel in the art.

Another object hereof is to provide an article 25 of the type described of novel and improved construction, all the parts of which are easy to assemble in proper relation one to the other, and all onto the frame which secures them into an entity.

30 Various other objects and advantages will become manifest as the disclosure proceeds.

In the accompanying drawings forming part of this application, similar characters of reference indicate corresponding parts in all the views.

35 Fig. 1 shows the back of a mirror provided with a pocket constructed in accordance with my present invention.

Fig. 2 is a section taken at line 2—2 in Fig. 1.

40 Fig. 3 shows an embodiment including that of Fig. 1, provided also with coin compartments and bill holder in accordance with the teachings of this invention.

Fig. 4 is an enlarged "exploded" section taken at line 4—4 in Fig. 3.

45 Fig. 5 shows the sheet component for covering the back of a pocket mirror.

Fig. 6 shows another sheet component used in the above constructions.

50 Fig. 7 shows the manner of assembling the aforesaid sheet components.

Fig. 8 shows a modification of the article illustrated in Fig. 1, whereby a coin case is produced.

55 Fig. 9 and Fig. 10 show the sheet components used for the embodiment of Fig. 8.

Fig. 11 shows a coin compartment member used in the article illustrated in Fig. 3.

Fig. 12 shows the manner of assembly of the member of Fig. 11 with that of Fig. 6.

Fig. 13 shows the manner of assembly of the 5 cover of Fig. 5 with the members of Fig. 12.

Fig. 14 shows the development of the bill holder included in the embodiment of Fig. 3.

Fig. 15 is a section through a closed bill holder.

In the manufacture of pocket mirrors, a sheet 10 of metal, usually soft iron, is placed between a silvered glass and a sheet of covering made of cloth, leather or other suitable material, with the ends of the latter overlapping the edges of the metal sheet. Then the edges of the metal 15 sheet are lapped over the glass whereby a unitary structure is formed.

In the drawings, the numeral 20 indicates a sheet member of leather or other appropriate material provided with a slit 21 of substantial 20 length, through which lies another sheet member 22, preferably of identical material, and the same are mounted in the manner aforesaid by a metal sheet 23 onto a mirror glass 24, which latter is thus covered and provided with a pocket opening 25 at said slit. Those ends of the sheet 22, which lie beyond the slit 21, are of course gripped by the metal member 23.

When a cover sheet 25 is provided with a wave-slit 26, so as to form fingers 27 and 28, and when 30 a sheet member 29 to be assembled with 25, in like manner as the sheets 20 and 22, is provided with a lace 30 having loops 31 to receive said fingers, and all assembled as aforesaid by an iron sheet onto a mirror glass, then we shall have 35 the coin case shown in Fig. 10, wherein 32 is a line of stitching off centre to form two compartments to receive coins of different size. The width of the fingers 27 and 28, are made less than the respective diameters of the coins 33 and 40 34, so that the latter may be visible. Of course, the stitching may be omitted, and generally speaking, the several features anywhere herein shown may be incorporated in ladies' hand bags and similar articles. 45

In the foregoing embodiments, the metal sheet 23, at most, clinches two thicknesses of sheet material at any one of its edges, and it is to be especially noted that any greater number would be both impractical and objectionable for several reasons, most important of which is that a secure joint could not be effected. Therefore I provide a construction whereby a sheet member which is so clinched, may receive in engagement 50 55

therewith one or more other sheets, whereby they become associated as the leaves of a book.

In the embodiment of Fig. 1, the sheet member 22, may just as well be substantially a rectangle. 5 Now however, said member is cut to have the pair of co-planar spaced tongues 35 and 36 at the bottom thereof, having rounded corners as at 37, and aligned slits or notches 38 at opposite sides of said sheet member, whereby said tongues issue 10 from member 22, each at an abruptly reduced width as at 39. It is evident that one or more other sheet members when provided with aligned slits or slots 40, may be engagingly received by the tongues 35 and 36, in the manner as shown 15 in Fig. 12. The length of any slit 40 is slightly greater than the width of the tongues at 39, whereby the sheets become associated page fashion.

For the embodiment shown in Fig. 3, I have 20 included one such additional sheet member designated generally by the numeral 41, having a flap portion 42, with an outwardly extending central tab 43, which latter is slit to form a lip 44. At the bend of said flap 42, the sheet 41, has cut 25 therein the oval holes 45, which permit the coins 46 in compartment 54, to be visible. The covering sheet 20, carries a lace loop 47, to receive tab 43 and for engagement with the lip 44. Said sheet 20, near the bottom edge thereof, has an eyelet 48 mounted, wherethrough passes a chain 49, or other flexible cord, which terminates at its exterior end in a ring or other stop member 50. The other end of this chain passes through the opening 51 which occurs at the line of junction of 30 the sheet members 22 and 41, and up through the compartment 52, the walls of which are such sheet members, and is secured to a bill holder generally designated by the numeral 53, which is adapted to reside in said compartment 52, taken 35 out therefrom and again reset therein by pulling the chain 49.

This bill holder is of leather or other suitable flexible material, and is fashioned out of a sheet slit to form the finger 55, about which bills are 45 wound flat. This sheet is folded at the base of the finger 55, whereby a book arrangement is formed, having in succession an uncut first page 56 provided with a tab 57 extending integral therefrom and bent over, said finger 55, and that 50 portion 58 of the sheet from which the finger was slit. The end of portion 58 is bent over to form a flap 59 to overlap both the finger 55 and the page 56; the tab 57 serving as a closing means.

I find it advantageous that the bill holder 53, 55 shall be slid out of its compartment 52, sufficient for access, but that it shall always partially remain in said compartment. I therefore provide slits 60, whereby the holder 53 may be slidably mounted on track tongue 61, shown dotted in Fig. 6, the lower end of which is clinched as are the tongues 35 and 36. The numerals 62 and 63 indicate slits cut in sheet 22.

This invention is capable of numerous forms and various applications without departing from 65 the essential features herein disclosed. It is therefore intended and desired that the embodiments shown herein be deemed illustrative and not restrictive, and that the patent shall cover whatever features of patentable novelty exist in 70 the invention disclosed; reference being had to the following claims rather than to the specific description herein to indicate the scope of the invention.

I claim:

75 1. In an article of the class described, the com-

bination with a metal sheet of a flexible sheet having a slit of substantial length intermediate its ends and a second flexible sheet positioned through said slit whereby one portion thereof is in surface contact with and lies between the 5 slitted and metal sheets, and the remainder thereof lies over and in surface contact with the slitted sheet; opposite ends of the metal sheet being overlapped by said flexible sheets and the ends of the metal sheet being folded over to clinch 10 the flexible sheets thereto.

2. In an article of the class described, the combination with a metal sheet of a flexible sheet having a wave slit to form a tongue, a second flexible sheet positioned through said slit whereby one portion thereof is in surface contact with and lies between the slitted and metal sheets and the remainder thereof lies over and in surface contact with the slitted sheet; opposite ends of the metal sheet being overlapped by said flexible sheets and the ends of the metal sheet being folded over to clinch the flexible sheets thereto. 25

3. In an article of the class described, the combination with a metal sheet, of a flexible sheet having a slit of substantial length intermediate its ends and carrying a loop in the region of said slit, a second flexible sheet positioned through said slit whereby a portion thereof lies over and in surface contact with the first flexible sheet, the remaining portion of the second flexible sheet terminating in a pair of tongues each having a slit open at opposite ends 30 of said second flexible sheet and which slits are colinear, and a third flexible sheet provided with a pair of colinear spaced slits intermediate its ends wherein said tongues respectively lie whereby the second and third flexible sheets are 40 engaged page-fashion at the slits in the second sheet; the third sheet lying between the first and second sheets; said third sheet extending at its free end through the slit in the first sheet and folded over, in which folded over portion a lip 45 is provided; said lip being adapted to engage the loop aforesaid; the first two sheets lying in contact with the metal sheet overlapping the edges thereof, and the ends of the metal sheet being folded over to clinch said overlapping 50 flexible sheets thereto, whereby two pockets are formed.

4. In an article as in claim 1, wherein the first flexible sheet is provided with an opening below the slit therein, including a bill holder comprising a folded sheet slit in one portion thereof to provide an extending finger for receiving bills thereabout and the other portion terminating in an outwardly extending tab adapted for engagement in the opening in the first portion of the 60 folded sheet, and a flexible cord member secured to said bill holder and lying between the flexible sheets with its free end passing through the aforesaid opening in the first flexible sheet whereby the bill holder is inserted between the 65 flexible sheets upon pulling the free end of said cord member.

5. In an article as in claim 1, wherein the second flexible sheet is provided with a loop of substantial length angularly disposed with respect to the slit in the first flexible sheet, including a bill holder comprising a folded sheet having openings near the fold thereof; said loop passing through said openings whereby the bill holder is slidably mounted on said loop for par- 75

tial emergence from between the flexible sheets.

6. In an article as in claim 1, wherein the second flexible sheet is provided with a loop of substantial length angularly disposed with respect to the slit in the first flexible sheet, including another sheet member having an open-

ing therein; said loop passing through such opening whereby said sheet member is slidably mounted on said loop for emergence from between the flexible sheets.

NAT W. UMANSKY.
